UNITED STATES PATENT OFFICE.

WESTON A. PRICE, OF CLEVELAND, OHIO, ASSIGNOR TO THE ELECTRIC AND DENTAL SPECIALTY COMPANY, OF CLEVELAND, OHIO, A CORPORATION OF OHIO.

DESIGN FOR AN AMMETER-COVER.

SPECIFICATION forming part of Design No. 36,398, dated June 30, 1903.

Application filed February 24, 1903. Serial No. 144,927. Term of patent 14 years.

To all whom it may concern:

Be it known that I, WESTON A. PRICE, a citizen of the United States, and a resident of Cleveland, county of Cuyahoga, and State of Ohio, have invented a new, original, and ornamental Design for Ammeter-Covers, of which the following is a specification, reference being had to the accompanying drawings, forming part thereof.

Figure I is a plan view of an ammeter-cover, showing my new design. Fig. II is a side view, and Fig. III is a front view thereof.

Having described my invention, what I claim as new, and desire to secure by Design Letters Patent, is—

The ornamental design for an ammeter-cover, as shown.

In testimony whereof I have signed my name to this specification in the presence of two subscribing witnesses.

WESTON A. PRICE.
